UNITED STATES PATENT OFFICE.

JOHN L. CREVELING, OF NEW YORK, N. Y., ASSIGNOR TO SAFETY CAR HEATING & LIGHTING COMPANY, A CORPORATION OF NEW JERSEY.

PNEUMATIC FAN.

No. 835,782.

Specification of Letters Patent.

Patented Nov. 13, 1906.

Application filed November 18, 1901. Serial No. 82,716.

To all whom it may concern:

Be it known that I, JOHN L. CREVELING, a citizen of the United States, and a resident of the city, county, and State of New York, 5 have invented certain new and useful Improvements in Pneumatic Fans, of which the following is a specification.

This invention relates to fans. One of the objects thereof is to provide a fan of simple 10 construction and efficient running qualities.

Another object is to provide a pneumatic fan of the above nature in which the air is utilized not only as a source of power, but as an effective means of ventilation.

15 Another object is to provide a pneumatic fan which may be readily maintained in a thoroughly lubricated state under conditions of high speed and pressure and in which the air is economically used.

20 Other objects will be in part obvious and in part pointed out hereinafter.

The invention accordingly consists in the features of construction, combinations of elements, and arrangement of parts which will 25 be exemplified in the construction hereinafter set forth and the scope of the application of which will be indicated in the following claims.

In the accompanying drawings, wherein is 30 shown one of various possible embodiments of my invention, Figure 1 is an end view thereof. Fig. 2 is a central sectional elevation.

Similar reference characters refer to similar 35 parts throughout both views of the drawings.

In order that certain dominant aims and features of this invention may be readily 40 grasped, it may here be noted that if it be attempted to utilize the motive fluid of a pneumatic fan for ventilation purposes there is a tendency of the same to become merely whirled out by centrifugal force and being in general of a relatively cool character to settle 45 to the floor immediately adjacent the fan, and thus become practically valueless with regard to the end in view. This is particularly true in cases analogous to railway-cars, in which a fan placed at the end of the car 50 will supply fresh air merely to its immediate neighborhood and leave the larger part of the car substantially unventilated. It may also be noted that in fans of the nature of that dealt with in the present invention the high

speed necessitates for efficient use an abundant lubrication of the bearings, and the high pressure under which the fan acts tends to blow oil from the bearings and interfere with lubrication, as well as waste the air. The above and other defects are eliminated and many advantages attained in constructions of the nature of that hereinafter described.

Referring now to Fig. 2 of the accompanying drawings, there is shown a support *a*, comprising a central casing *b* and a skirt *c*, adapted to fit against the wall. Leading to casing *b* is an air-supply pipe *d*, which may be connected with the air-braking system of a train should the fan be used in such relation. Threaded within support *a* is a casting *e*, having in turn threaded therein a bushing *f*, and provided with an oil-receptacle *g*, substantially of the form shown. Formed within oil-chamber *g* is a sleeve *h*, which serves as a bearing for the end *k* of a hollow shaft *j*, these parts conjointly constituting a fluid-transmitting means for the fan, as hereinafter described. It may here be noted, however, that the term "fluid-transmitting means" as used throughout the following claims is sufficiently broad to cover a conduit of whatever character. The bearing of shaft *k* within sleeve *h* is preferably somewhat loose, and any air leaking through the same is permitted to escape through a vent *g* in chamber *g*, thus preventing any accumulation of pressure therein and consequent tendency to blow oil from the main bearing of the shaft *j* within the fitting *i*, as shown in the drawings. Shaft *j* is preferably formed of steel or other material adapted to withstand the wear to which this part is subjected in use; but the part *k* is composed of bronze or the like to adapt it to withstand the effect of any moisture which may be present in the air passing the same. The lubrication of the bearing of extension *k* is brought about through a rawhide washer *m*, resting against a shoulder *l*, formed upon the shaft and held at its outer edges against the casting *e* by the above-described bushing *f*. A wick *o*, one end of which dips within the lubricant in oil-chamber *g*, contacts at its upper end with the washer *m* and by capillary action supplies oil thereto. This oil is carried by the slight amount of air leaking past the washer *m* into the bearing of extension *k*, and thus main-

tains this part in a thoroughly lubricated condition, any excess of lubricant being returned from the inner end of the sleeve *h* to the oil-chamber *g*. Formed upon shaft *j* is a shoulder *p*, adapted to engage the inner end of the fitting *i*, and thus serve as a bearing to take up the thrust exerted upon the shaft by the incoming air. The latter bearing, as well as the main bearing of shaft *j*, are lubricated from an oil-cup *q* by means of wicks *r* and *s*, the former being spring-pressed into operative relation to the shaft, as shown in the drawings.

Threaded upon the outer end of the shaft *j* is a four-arm fitting or fan-head *t*, the joint being covered by a shield *u*, provided with a vent *v*. Through each arm of the fan-head *t* is formed a passage *w*, and mounted thereon are fan-blades *x*, the shape of which is best shown in Fig. 1 of the drawings. To each arm of head *t* is connected a tube *y*, provided with a cap *z*, in which are formed discharge-ports *1*, through which the reactive jets are effected for the propulsion of the fan. These jets, as will be noted by reference to Fig. 2 of the drawings, are so disposed and directed as each to discharge within the path of the following blade, and thus be engaged thereby and forcibly thrown in a direction parallel to the shaft of the fan. Each fan-blade, moreover, is formed with a lateral extension *3*, as shown in Fig. 1, so as to adapt the same to coact with the jets of the preceding blade and act substantially exclusively thereon.

The operation of the above-described embodiment of my invention is substantially as follows: Air being supplied through pipe *d*, the same passes through the bushing *f* and thence through the composite shaft comprising members *j* and *k* to the fan-head. From this point the air is carried out in a radial direction and discharged, as above set forth, exactly within the sweep of the following blade, upon which it impinges and by which it is thrown in the desired direction. Each set of discharge-jets thus supplies the following blade with air upon which to act, and the same acts upon this fresh outer air rather than upon the foul air of the room, which would otherwise be supplied thereto by the partial vacuum in the rear of the preceding blade. In this manner a column of substantially pure air is forcibly thrown into the room and results in a highly uniform and efficient ventilation thereof. The shape of the fan-blade, moreover, is such as to coact with these discharge-jets and enhance the effectiveness of the above action. Any tendency to blow the lubricant from the bearing adjacent the source of air-supply results merely in forcing an additional amount of lubricant into the same from the saturated washer *m*, and any excess of oil is automatically returned to the oil-cup. The main bearing of shaft *j* is thus protected from the

effect of the air by the vented cup *g* and is thoroughly lubricated by the capillary means above set forth, which are substantially unaffected either by air-pressure or gravity. The action of the air-pressure, moreover, upon the oil-soaked washer *m* tends to cause the same to hug the end of the rotating shaft more closely, and thus more efficiently seal the joint between the same and the member in which it is journaled.

It will thus be seen that I have provided a device in which the several aims of my invention are achieved and in which the above-enumerated advantages are, among others, present in a marked degree. The entire mechanism is of simple and inexpensive construction, automatically maintains itself in a thoroughly-lubricated condition, and is characterized by an efficient and economical use of the fluid supplied thereto.

As many changes could be made in the above construction and many apparently widely-different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention which, as a matter of language, might be said to fall therebetween.

Having described my invention, what I claim, and desire to secure by Letters Patent, is—

1. In a pneumatic reaction-fan, the combination of fan-blades provided with channels or conduits provided for the exit of air and a compound hollow shaft carrying the fan-blades, a bearing and a washer of rawhide or other absorbent material barring the passage to the bearing, the portion of the shaft in contact with the said washer being of bronze or other difficultly-oxidizable material.

2. In apparatus of the class described, in combination, fluid-transmitting means, revolvably-mounted fluid-discharging means connected therewith, and means comprising a rotary fan connected with and adapted to be driven by said discharging means, said discharging means being directed into the path of travel of a blade of the fan.

3. In apparatus of the class described, in combination, fluid-transmitting means, revolvably-mounted fluid-discharging means connected therewith, and means comprising a rotary fan connected with and adapted to be driven by said discharging means, said discharging means being positioned within the path of travel of a blade of said fan and discharging in a direction substantially parallel to the plane of its movement.

4. In apparatus of the class described, in combination, fluid-transmitting means, revolubly-mounted fluid-discharging means connected therewith, the point of discharge thereof being spaced from its axis of revolution, and means comprising a rotary fan connected with and adapted to be driven by said discharging means and having a blade enlarged at a distance from the axis substantially corresponding with said spacing of the point of discharge, said fluid-discharge means being directed into the path of travel of a blade of the fan.

5. In apparatus of the class described, in combination, fluid-transmitting means, revolubly-mounted fluid-discharging means connected therewith, the point of discharge thereof being spaced from its axis of revolution, and means comprising a rotary fan connected with and adapted to be driven by said discharging means and having a blade enlarged at a distance from the axis substantially corresponding with said spacing of the point of discharge, said discharging means being positioned within the path of travel of said enlarged blade of said fan and discharging in a direction substantially parallel to the plane of its movement.

6. In apparatus of the class described, in combination, rotary fluid-driven means, a hollow shaft upon which said means are mounted adapted to transmit fluid thereto, a member through which said shaft passes toward a source of compressed-fluid supply, and means comprising a flexible washer held against said member and extending over said shaft adapted to permit the entry of said fluid within said shaft and to tend to prevent its passage between said shaft and said member.

7. In apparatus of the class described, in combination, rotary fluid-driven means, a

hollow shaft upon which said means are mounted adapted to transmit fluid thereto, a member through which said shaft passes toward a source of compressed-fluid supply, means comprising a flexible washer held against said member and extending over said shaft adapted to permit the entry of said fluid within said shaft and to tend to prevent its passage between said shaft and said member, an oil-chamber through which said shaft passes, and means adapted to feed oil from said chamber to said washer.

8. In apparatus of the class described, in combination, rotary fluid-driven means, a hollow shaft upon which said means are mounted adapted to transmit fluid thereto, a member through which said shaft passes toward a source of compressed-fluid supply, a vented oil-chamber through which said shaft passes upon the outer side of said chamber, a bearing within which said shaft is journaled upon the outer side of said oil-chamber, and means adapted to transmit oil from said chamber to the inner side of said member adjacent said shaft.

9. In apparatus of the class described, in combination, rotary fluid-driven means, a hollow shaft upon which said means are mounted adapted to transmit fluid thereto, a member through which said shaft passes toward a source of compressed-fluid supply, and means comprising a flexible washer held against said member and extending over said shaft adapted to permit the entry of said fluid within said shaft and to tend to prevent its passage between said shaft and said member, said shaft being provided with a hollow projection passing through said washer.
